CLAIM

An ornamental design for a two part magnetic sensor, as shown and described.

DESCRIPTION

FIG. 1 is a top side and front isometric view of a two part magnetic sensor and showing my design;

FIG. 2 is a top view of one of the parts thereof;

FIG. 3 is a front elevational view of the one part thereof, the rear elevational view being a mirror image;

FIG. 4 is a bottom plan view of one part thereof;

FIG. 5 is a right side elevational view of one part thereof, the left side elevational view being a mirror image;

FIG. 6 is a top plan view of other part thereof;

FIG. 7 is a left side elevational view of other part thereof, the right side elevational view being a mirror image;

FIG. 8 is a front elevational view of other part thereof, the rear elevational view being a mirror thereof; and,

FIG. 9 is a bottom plan view of other part.
